UNITED STATES PATENT OFFICE.

PEREZ C. RICH, OF BOSTON, ASSIGNOR TO CHARLES J. BAILEY AND JULIUS M. CLAPP, BOTH OF NEWTON, MASSACHUSETTS.

RULER.

SPECIFICATION forming part of Letters Patent No. 297,717, dated April 29, 1884.

Application filed February 29, 1884. (No model.)

To all whom it may concern:

Be it known that I, PEREZ C. RICH, of Boston, county of Suffolk, State of Massachusetts, have invented an Improvement in Rules, of 5 which the following description, in connection with the accompanying drawings, is a specification, like letters on the drawings representing like parts.

This invention has for its object the production of a ruler which may be used either as a pen or pencil ruler and as a roller or a flat rule, the same being adapted to be rolled over the paper and draw or push the flat rule equally at both ends for the production of parallel 15 lines. In this my invention an ordinary roller or cylinder and an ordinary flat bar are jointed together, so that the flat bar, when used, may lie flat upon the paper, whichever side is down. I have provided the roller with a scale to 20 operate with a pointer, so that the extent of movement of the roller over the paper may be indicated accurately.

Figure 1, in perspective, represents a ruler embodying my invention, the flat bar being in 25 position for use with a pencil; Fig. 2, a like view with the flat bar in position for use with a pen; Fig. 3, an enlarged left-hand end view of Fig. 1, and Fig. 4 an enlarged view of the roller from its upper side.

30 The roller A and the flat bar B are supposed to be of wood or any suitable material, and of usual shape. These parts are joined by metal links C, connected with them by screws 2, the said links being slotted at c to receive the 35 screw or stud c', which acts as a stop to permit the flat bar to turn on the screws 2, so that either side of the said bar, when down, may rest flat upon the paper, Figs. 1 and 2 showing the said flat bar in its two positions.

40 In Fig. 1 the ruler is adapted for use with a pencil, and in Fig. 2 with a pen. The edge of the flat bar may, if desired, be provided with a strip, b, of brass or other metal. The end

of the roller is provided with a scale to indicate fractions of inches, and the link C has a 45 pointer, 4, to co-operate therewith, so that should it be desired to mark section or parallel lines the roller may be rolled on the paper for a measured distance, thus placing the edge b of the flat rule just the proper place to 50 make section-lines one after another at a uniform distance apart and parallel. The scale 5 may be marked in the roller or made in a metal ferrule applied to the roller.

It will be noticed in my improved ruler that 55 the roller and the flat bar always rest directly upon the paper at the same time, and the flat side, not the edge, of the bar rests upon the paper.

I claim—

1. As an improved article of manufacture, a ruler composed of a roller and a bar loosely connected each with the other by links which hold the pivots for the bar, whereby the ruler may be used at will with either side of the bar 65 uppermost, the under side thereof then resting flat on the paper below it, to operate substantially as and for the purpose described.

2. In a ruler, a roller and flat bar joined together by links, and having a stop to arrest 70 the movement of the bar with relation to the roller, whereby either side of the flat ruler may be laid upon the paper, substantially as described.

3. In a ruler, a roller and flat bar and links 75 to join them, the said roller being provided with a scale, and the links with an index to operate, substantially as described.

In testimony whereof I have signed my name to this specification in the presence of two sub- 80 scribing witnesses.

PEREZ C. RICH.
